S. J. DUNKLEY.
LYE REGULATOR FOR PEACH PEELING MACHINES.
FILED AUG. 8, 1921.

UNITED STATES PATENT OFFICE.

SAMUEL J. DUNKLEY, OF OAKLAND, CALIFORNIA.

LYE REGULATOR FOR PEACH-PEELING MACHINES.

Application filed August 8, 1921. Serial No. 490,752.

To all whom it may concern:

Be it known that I, SAMUEL J. DUNKLEY, a citizen of the United States, residing at Oakland, county of Alameda, State of California, have invented certain new and useful Improvements in Lye Regulators for Peach-Peeling Machines, of which the following is a specification.

This invention relates to a means for regulating and controlling the strength of the lye solution in a lye peach peeling apparatus.

The objects of the invention are to provide complete automatic control of the strength of the lye or other disintegrating solution.

Objects of the invention pertaining to economies and details in construction and operation will definitely appear from the detailed description to follow.

I accomplish the objects of my invention by the apparatus and means described in the following specification. The invention is clearly defined and pointed out in the claims.

A structure which is a preferred embodiment of my invention is illustrated, largely diagrammatically, in the accompanying drawing forming a part of this specification in which:

Fig. I is a detail side elevation view of my improved apparatus as applied to the lying section of a peach peeling machine, certain parts being merely indicated in diagram.

Fig. II is an end elevation sectional view of the structure taken on the irregular line 2-2 looking in the direction of the arrows of Fig. I, showing certain details of the circulation means.

Fig. III is an enlarged detail view through the automatic hydrometer control section, the hydrometer tank and the hydrometer guard being in section.

In the drawing similar numerals of reference refer to similar parts throughout the several views.

Considering the parts by their reference numbers, 1 is the lying section of one of my improved peach peeling machines similar to that illustrated in my patent application dated January 8, 1921, Serial No. 435,979. 2 is the main tank which also is the means for collecting the used lye from the peaches, the same having been first strained and cleared of the disintegrated peach peel and other débris by the screen means 12. 3 is the heating and pressure

tank supplied with suitable steam heating coils.

Lye is taken from the tank 2 by the centrifugal pump 4 through the suction pipe 5 and discharged into the tank 3 through the pipe 6. Tank 2 is also supplied with water to keep up the volume. The same may be controlled by suitable overflow.

The heated lye passes from the pressure tank 3 through pipe 7 up by the side of the lying section of my improved peach peeler and when the machine is in operation delivers to the spray nozzles through the valves 8-8 (see Fig. I).

Pipe 7 in reduced section is continued at 7' for circulation purposes and for the purpose of dissolving and admixing additional caustic soda into the lye to maintain the strength. Shut-off valve 13 is provided for this pipe.

The lye-mixing tank 9 is like that appearing in my Patent No. 1,374,291, the details of which I do not here illustrate as they are no part of my present invention.

Pipe 10 leads from valve 13 to tank 9 and is provided for delivering water or the weakened lye solution into this tank 9 so that it will dissolve and take up additional caustic soda. When the lye solution from this tank is strengthened it is discharged by gravity through the pipe 11 into the main tank 2 and increases the strength of the solution therein. A cock 11' is provided in pipe 11.

Pipe 14 branches from the pipe 7' downwardly, being controlled by valve 14', and delivers into the hydrometer tank 15. The hydrometer 16 is disposed herein in a suitable hydrometer guard and guide 16'. The upper end of the hydrometer float 16 is connected to the end of the lever 17, which lever is fulcrumed at 18 and is provided with a binding post 21 that connects to an electric line and delivers through a conductor plate and contact means 21' through contacting with the lower end of the binding post 22 supported and carried by the adjustable collar 23 to the motor. A pointer 24 carried by adjustable collar 23 indicates on the scale 25 the elevation of the adjustment of this contact device which, of course, regulates the density because of the relative elevation of the hydrometer bulb 16. The hydrometer bulb is protected from agitation by the contents of tank 15 by the baffle plate 19 extending up in front of the intake of the pipe 14 and the baffle 20 beyond the same, projecting down from the top of the tank 15 so that

there is only a gradual even flow of fluid through this tank which overflows through the comparatively large pipe 15' downwardly into the circulation return pipe 11.

5 An auxiliary centrifugal pump 26 is provided and is electrically driven by the motor 27. The current to this motor is controlled by the hydrometer float as already pointed out.

10 The intake 28 of pump 26 connects to the tank 2 and its delivery is through pipe 29 to the circulation pipe 10 delivering into the mixing tank 9. (See Fig. I.)

I have now described the various parts of 15 my improved structure and I will indicate their operation. The object of the principal machine is to deliver hot lye through the pipe 7 to the lying section through the valves 8—8. Of course, the lye is used up or 20 consumed by this process. As much of it, however, as possible is recovered and strained through the strainer 12 and passes down into the tank 2. The volume of solutions is maintained in this tank by adding 25 water, which may be done through suitable overflow or otherwise. The pump 4 draws from this supply tank and delivers into the heating and pressure tank 3 from which the lye passes up through the pipe 7. This is 30 the main circulation of the machine and but for the need of the maintenance of the strength of the lye would be all that is required. However, it is important to keep the strength of the lye constant and to that 35 end the mixing tank 9 is provided for dissolving caustic soda to supply the tank 2 as rapidly as it may be needed. To accomplish this a small quantity of the lye is allowed to pass through the pipe 7 down through 40 the pipe 14 to the hydrometer tank 15. When it becomes weakened the hydrometer float 16 is no longer sustained but drops down actuating the balanced lever 17 on its fulcrum 18 and closing the electric circuit 45 to the motor 27. This starts the auxiliary pump 26 which withdraws weakened solution from the tank 2, passing it up through the valved discharge pipe 29 through the pipe 10 into the mixing tank 9 50 where it takes up additional quantity of the caustic soda or other disintegrating material which then passes out at the bottom of the mixing tank through the pipe 11 to the tank 2, thereby adding the caustic soda to the 55 contents of that tank and raising its density.

This, of course, is effectively mixed by the circulation and is passed to the heater pressure tank 3 and, of course, the strengthened solution then passes through the pipe 7 and 60 thence to pipe 7' to the pipe 14 into the hydrometer tank 15. When the density of this solution has been raised to the desired predetermined point, it forces the float 16 of the hydrometer up, breaks the circuit at the 65 point of contact between plate 21' and the

lower end of the binding post, and stops the electric motor.

I have shown this in the simplest form but any usual automatic switch connections are provided in this behalf which I have not deemed it necessary to here illustrate.

When the strength of solution again falls the cycle of operation is again put into action so that the strength of the solution is at once brought up to standard and rarely 75 drops more than a small fraction below the standard before the apparatus acts.

In starting my improved apparatus the tank 2 is filled with water and the pump 4 is started, delivering the water through the 80 pipes 7 and 7'. The valve 13 is opened so that the main pump delivers the water very rapidly through the mixing tank 9 and brings the lye up to the initial strength. When the desired strength is approached 85 the valve 13 may be closed to bring the hydrometer control into action.

While I have described my improved apparatus as applicable to caustic soda lye it would, of course, be applicable to any disintegrating solution, the specific gravity of which would be varied by the addition of 90 disintegrating material employed.

I have shown motor means actuated electrically, but other means might be provided 95 that would be under the control of the hydrometer so that the auxiliary circuit could be brought into action. These I do not deem necessary to illustrate as they could be readily developed by any skilled mechanic.

I have shown the parts here largely diagrammatically without illustrating the details of the various operating mechanisms. Such operating mechanisms are now well-known and are further illustrated in my 105 patent applications referred to.

My invention is applicable to a great variety of uses and will, of course, control by the auxiliary means and a hydrometer the strength of any solution which is varied by 110 the addition of a chemical or any material to be dissolved.

My improved regulating means are thus capable of general use wherever it is desired to maintain the strength of a solution. 115 I, therefore, state that I desire to claim the invention broadly and also specifically in its various relations and aspects as pointed out in the appended claims.

Having thus described my invention what 120 I claim as new and desire to secure by Letters Patent is:

1. In a lying apparatus the combination of the main tank, a heater tank and main circulating connections therefrom to supply 125 the lye for the lying purposes, a recovery means for collecting the used lye and returning the same to the main tank a lye mixing tank, an auxiliary circulating connection from the main tank to deliver to the said 130

- mixing tank comprising a pump, a return from the bottom of said mixing tank to the said main tank, an electric motor for driving said auxiliary pump, a hydrometer, a by-pass circuit in the main circulating system delivering to the said hydrometer, an electric switch actuated by the said hydrometer to automatically close the circuit to start the said auxiliary motor at any predetermined 5 position of the hydrometer, coacting substantially as described for the purpose specified.
2. In a lying apparatus the combination of the main tank, a heater tank and main circulating connections therefrom to supply 10 the lye for the lying purposes, a recovery means for collecting the used lye and returning the same to the main tank, a lye mixing tank, an auxiliary circulating connection from the main tank to deliver to the said 15 mixing tank comprising a pump, a return from the bottom of said mixing tank to the said main tank, an electric motor for driving said auxiliary pump, a hydrometer, a bypass circuit in the main circulating system delivering to the said hydrometer, an electric switch actuated by the said hydrometer to automatically close the circuit to start the said auxiliary motor, coacting substantially as described for the purpose specified.
3. In a lying apparatus the combination of the main tank, a main circulating connection therefrom to supply the lye for use, a lye mixing tank, an auxiliary circulation means delivering to the said lye mixing 20 tank, electric means for controlling the auxiliary circulating means to the mixing tank, a hydrometer connected and disposed to be acted upon by the fluid of the main tank, electrical connections controlled by the operation of said hydrometer for controlling the electric means of said auxiliary circulating connection to the mixing tank, coacting as specified.
4. In an apparatus of the class described the combination of the main tank, means for 45 circulating the contents therefrom, a mixing tank, an auxiliary circulating means supplied from the main tank to pass through the mixing tank, a hydrometer for indicating the strength of the solution of the main 50 tank, and electric control means actuated by the hydrometer for regulating the flow to the mixing tank, as specified.
5. In an apparatus of the class described, the combination of a main tank, a mixing 55 tank, means to deliver from the mixing tank to the main tank, a hydrometer acted upon by the solution from the main tank, electric means for controlling the flow from the mixing tank to the main tank and connections 60 from the hydrometer to control the said electric means, as specified.
6. In an apparatus of the class described the combination of the main tank, a mixing tank for supplying additional chemical de- 65 livering to the main tank, a hydrometer disposed to be acted upon by the solution of the main tank, a means to deliver from the mixing tank to supply the main tank, and electrical means associated with and actuated 70 by the hydrometer for controlling a means for delivering liquid from the main tank to the mixing tank.
7. A hydrometer control means to regulate a solution, a tank to receive the solution 75 to be regulated, a hydrometer float disposed to be acted upon by the said fluid, delivery means for supplying material to the solution and electrical control means therefor comprising an adjustable member disposed to be 80 actuated by the hydrometer float, as specified.

In witness whereof, I have hereunto set my hand and seal.

SAMUEL J. DUNKLEY. [L. s.]
